UNITED STATES PATENT OFFICE.

JOHN T. CROWLEY, OF BEACON FALLS, CONNECTICUT, ASSIGNOR TO THE BEACON FALLS RUBBER SHOE COMPANY, OF BEACON FALLS, CONNECTICUT, A CORPORATION OF CONNECTICUT.
MINER'S SHOE.

1,155,644.

Specification of Letters Patent.

Patented Oct. 5, 1915.

Application filed September 1, 1914. Serial No. 859,600.

To all whom it may concern:

Be it known that I, JOHN T. CROWLEY, a citizen of the United States of America, residing in Beacon Falls, in the county of New Haven and State of Connecticut, have invented certain new and useful Improvements in Miners' Shoes, of which the following is a specification.

This invention relates to rubber footwear, and has for its object to provide an improved miner's shoe of such construction that the same will be easy to manufacture and economical in use. This shoe, although primarily designed for use in the mines, is equally capable of being used by woodsmen, hunters, and farmers, and in fact in any situation where the upper of the shoe is subjected to hard usage.

In one form of miner's shoe now largely in use, the opening is at the front and the shoe is of Blucher formation, and the ears of the quarters protrude in such a way that they catch in the coal and the miners experience considerable trouble with their shoes giving out at this point. Another difficulty experienced is that the laces with which the sides are connected and which pass through eyelets located at the edges of the side flaps, press upon the tongue where they cross in front and soon cut through the tongue owing to the movement of the foot of the wearer.

In my improved shoe the lacing is placed at the side, thus leaving the front of the shoe clean and unencumbered with protruding edges which are liable to catch in obstructions, and wherein the eyelets for the laces are provided on the outside, and in such a manner that the lacing cannot come in contact with the bellows tongue, which tongue is preferably of a peculiar formation presently to be described.

In the drawings accompanying this specification, one practicable embodiment of the invention is illustrated, in which drawings—

Figure 1 is a side elevation of my improved shoe; Fig. 2 is a top view of the upper; and Fig. 3 is a view similar to Fig. 1 but showing the sides drawn apart and the tongue distended.

The upper of the shoe, represented by 7, is preferably made of such dimensions that the meeting edges 8, 8, of the opening will come together when the shoe is upon the foot and laced up. A bellows tongue or pocket

9 is located inwardly of the opening which is disposed at the side of the shoe. In making the shoe the tongue will be formed in position very much as illustrated in the drawings, particular reference being had to Fig. 2, such tongue being given four folds, 10 and 11 at the inside and 12 and 13 outwardly of the center portion 14 of the bellows. The folds 12 and 13 preferably meet along the line of the opening demarcated by the edges 8, 8. But in practice it is preferable to form the upper without an opening and vulcanize the same. After the vulcanization the upper will be slit at 15 in Fig. 2 forming the side opening having the edges 8, 8. It will be seen that the tongue is fan-shaped when spread out as in Fig. 3 for the purpose of putting on or removing the shoe, and that the same narrows down perceptibly toward the foot of the shoe. This narrowing is of particular advantage when the opening in the upper is fastened, the tongue folding compactly and tapering down will not materially interfere with the foot of the wearer. Not only is it desirable to place the opening in the upper at the side of the shoe, but it will be seen that by forming the opening and tongue according to my invention, the body of the upper comes closely together and is free from extruding parts.

A shoe of this character must necessarily have some fastening means to hold the edges together. Such fastening means are of some suitable form, but preferably in the form of lacing. It is quite important in applying the fastening means that the body of the upper shall not be weakened thereby nor openings produced which afford an entrance for water. In addition to this the fastening must be so located that the tongue is shielded from contact therewith, otherwise the tongue will become worn or cut and the waterproof character of the shoe destroyed.

In the present illustration the eyelets for the lacing are afforded by a series of harness D's, 16, which are secured in place upon the upper by means of suitable straps or lugs 17 vulcanized in position. These D's form suitable eyelets for receiving the heavy lacing which is generally used on shoes of this character. These eyelets are secured in position when making up the shoe and are securely vulcanized in position. By reference to the drawings it will be seen that the eyelets are located at an appreciable distance

- from the edges 8, 8, of the opening, and that they are disposed upon the outside of the shoe in such a position that neither they nor the lacings come in contact with the tongue, and that they are also located in such position that the edges 8, 8 may be drawn and held together, thereby further safeguarding the tongue and enhancing the life thereof.
10. It will be understood that the shoe shown in the drawings is illustrative of the invention, and that changes may be made within the scope of the claims without departing from the spirit of the invention.
15. I claim as my invention:
1. A rubber shoe having the front closed and free from obstruction and having an opening disposed rearwardly of such closed front, a rubber tongue located inwardly of such opening, and lacing eyelets disposed entirely on the outside of the upper adjacent the edges of the said opening, the parts being located in such relative positions that the lacings in said eyelets are kept out of contact with the tongue.
  2. A rubber shoe having a bellows tongue located at the side and formed with four folds, two of such folds abutting one another and being disposed medially of the other folds, the upper being formed continu-
- ous outwardly of such tongue and slit along the medial line of said abutting folds.
3. A rubber shoe having a bellows tongue located at the side and formed with four folds, two of such folds abutting one another and being disposed medially of the other folds, the upper being formed continuous outwardly of such tongue and slit along the medial line of said abutting folds, and fastening means located upon the outside of the upper adjacent said slit.
4. A rubber shoe having a bellows tongue located at the side and formed with four folds, two of such folds abutting one another and being disposed medially of the other folds, the upper being formed continuous outwardly of such tongue and slit along the medial line of said abutting folds, and lacing loops secured upon the outside of the upper adjacent said slit, and lacing carried by said loops exterior to the upper and in position away from the tongue.

In witness whereof, I have hereunto signed my name in the presence of two subscribing witnesses.

JOHN T. CROWLEY.
